UNITED STATES PATENT OFFICE

SAMUEL MARCUS, OF BROOKLYN, AND ALEXANDER KONOFF, OF NEW YORK, N. Y.,
ASSIGNORS TO MARKON MANUFACTURING CO., INC., OF NEW YORK, N. Y., A COR-
PORATION OF NEW YORK

ROLLING EYES WITH LASHES

Application filed November 1, 1927. Serial No. 230,231.

This invention relates to rolling eyes with lashes, the invention being particularly, though not necessarily exclusively, directed to the provision of an improved eye set for dolls.

An object of the invention is to provide a simple, efficient and practical arrangement of parts whereby the eye set will include eyes movable not only to "open" and "closed" position but also from side to side, and in which an eyelash member is present arranged to move to "open" and "closed" position.

A further and more detailed object is to provide improved and simplified means for holding the eyelash members in appropriate position with respect to the eye shells, and to provide bumper parts in association therewith for limiting movement of the whole.

A further detailed object is to so construct the parts as to provide for all necessary manual adjustment of the eyes whereby they may be made to correctly fit in operative position in a given doll head.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which we have shown merely a preferred form of embodiment of the invention:—

Fig. 1 is a rear elevational view of an eye set constructed in accordance with this invention, being shown partly in vertical section, and in association with the representation of a doll head also appearing in vertical section.

Fig. 2 is a horizontal sectional view taken upon the plane of line 2—2 of Fig. 1, and

Fig. 3 is a vertical sectional view taken upon the plane of line 3—3 of Fig. 1.

Referring to the drawings for describing in detail the structure illustrated therein, the reference character L indicates an ordinary

doll head having the usual eye openings 1 and 2 through its frontal portion.

Arranged within the openings 1 and 2 are the two eye shells as G and H, said shells being connected with a common cross rod 3 which extends horizontally of the head and which is supported by its mid section through the medium of a suitable supporting carrier as 4 through which it passes and which is in turn connected with the material of the doll head intermediate the eye openings 1 and 2.

The form of cross rod support indicated corresponds in general with the structure shown and described in the pending application of Samuel Marcus, Serial No. 163,610, though it will of course be understood that any other appropriate form of cross rod support may be employed as may be found most suitable.

At one end of the cross rod is a connector member 5 by which the adjacent eye shell is connected with the cross rod, and at the opposite end of the cross rod a similar connector member as 6 is arranged for connecting the second eye shell with the cross rod. These connector members are of the general form as shown and described in the pending application of Samuel Marcus and Alexander Konoff, Serial No. 216,530, in that they each consist of a body part 7 having a central opening 8 through which the cross rod extends and having slits as 9 and 10 extending from opposite sides of said opening so that at least one side part as 11 of the body is rendered resilient for thereby frictionally engaging and gripping the cross rod, the opening 8 being normally of slightly less diameter than the diameter of the cross rod so that the part 11 will be sprung to admit the cross rod. At the upper and lower ends of the body 7 suitable pivot extensions as 12 and 13 engage within bearing apertures as 14 and 15 respectively of the eye shell and thereby constitute a pivotal mounting for the eye shell upon a vertical axis, these pivot parts being so positioned that the pivotal axis will intersect the spherical centre of the eye shell.

From the lower marginal edge of each eye shell extends a weight arm as 16, the lower ends of said arms being connected by a link 100

17 carrying a weight 18, whereby the eye shells will move in unison from side to side whenever the weight is shifted sidewise, after the manner shown and described in said application Serial No. 216,530 now Patent No. 5 1,727,477, dated September 10, 1929.

Any appropriate expedient may be resorted to for permitting the necessary extent of side- 10 wise pivotal movement of the eye shells without interference from the cross rod, but as clearly seen in Fig. 2 it is suggested that the portions of the cross rod which stand adjacent the rear edge parts of the eye shells may be looped backwardly, as at 19 and 20 to thus 15 provide the required clearance, said parts incidentally also serving, when engaged by the edge parts of the eye shell when fully thrown, to limit the sidewise movement of the eye shells.

20 By reason of the fact that the cross rod is pivotally mounted in the supporting carrier 4 in axial alignment with the spherical centres of the eye shells it follows that the weight 18 also constitutes a gravity control for swing- 25 ing the eyes between "open" and "closed" positions, this movement being of course about a horizontal axis longitudinally of the cross rod.

20 A stop member as 21 is provided for limit- 30 ing the "open" and "closed" positions of the eyes. This member consists of a strip of material, which is preferably spring metal, fixed by its mid portion to one of the connector members 7 and having its lower end 35 part as at 21 projecting below the eye arranged to engage an interior surface portion of the head for limiting the open movement of the eyes and having its upper end as at 23 projecting above the eye arranged to engage 40 a different surface portion of the head for limiting the closed position of the eye.

There may be a bumper device of this character connected with each eye as shown if desired.

45 The eyelash member for each eye is indicated by the reference character 24. It is connected to and projects below the lower edge of a semispherical shell part 25 which overlies the upper portion of the eye shell and is 50 shaped and colored in its exposed portion to represent an eyelid in the customary and appropriate position with respect to the iris picture which it will be understood is of course carried by the eye shell.

55 This eyelid member and the eyelash supported thereby is provided with a rearwardly extending strip 26 which continues to the rear of the eye shell and extends downwardly across the open rear side of the shell, being 60 fixed to the connector member 7 so as to move with said connector member at all times, from which it will be apparent that whenever the doll is moved between upright and reclining positions the gravity acting weight 18 will 65 swing both the eye shell and the lid, with the

eyelash, correspondingly between "open" and "closed" positions, while when the doll is tipped from side to side the weight will swing the eye shell from side to side without imparting a corresponding movement to the 70 eyelid or lash.

The manner of connecting the eyelid members and the bumper members with the connector members may take any appropriate form. In the instance illustrated the connection is accomplished by providing a plurality of tangs as 27 and 28 projecting rearwardly from each connector member, being inserted through mating openings in the respective eyelid and bumper members, and being clinched down over the rear surface of said members so that in effect the several parts are firmly riveted together. 75 80

It is noteworthy that the bumper members are adapted for adjustment by bending so 85 that they will strike against opposing parts of the doll head at proper times. The parts 23 have reduced portions as 29 for facilitating bending of said parts 23, while the parts 22 have off-set sections as 30 for facilitating 90 the bending adjustment of said parts 22. Bending adjustment of either of these parts will in no wise interfere with any other part of the eye set structure.

The weight arms 16 are bendable in the 95 localities indicated by the reference character 31 for facilitating independent adjustment of the eye shells about their vertical axes.

100 The material from which the eyelid member is constructed, together with its form, is such as to permit of easy bending adjustment of the lid portion with respect to the point of attachment with the connector member for enabling adjustment of the lid to a proper fit with respect to the underlying eye shell or to the eye opening of the doll head within 105 which it moves.

110 The eye set as thus disclosed will admit of manual adjustment of the eye shells, with 115 their respective connected parts, longitudinally of the cross rod toward and away from each other, or rotatably of the cross rod independently of each other. Or the eyes may be adjusted with respect to each other rotatably upon their vertical pivots, or the eyelids may be adjusted in any direction for properly fitting about the respective eye shells or into the adjacent eye openings. And 120 withal the structure is simple, substantial and practical throughout.

125 As many changes could be made in this construction without departing from the scope of the invention as defined in the following claims, it is intended that all matter contained in the above description, or shown in the accompanying drawings, shall be interpreted as illustrative only and not in a limiting sense.

Having thus described our invention, what 130

we claim as new and desire to secure by Letters Patent is:—

1. In an eye set, a pair of eyes, a supporting member extending between said eyes, connector members one for connecting each of the eyes with the supporting member, said connector members comprising parts providing for manual adjustment of the connector members rotatably and longitudinally of the supporting member, said connector members also having pivot parts by which the respective eyes are pivotally connected thereto to swing about vertical axes, a carrier for the supporting member permitting pivotal movement of the eyes with the supporting member upon a horizontal axis, eyelids fixedly connected directly with the connector members so as to be adjustable therewith rotatably of the supporting member and so as to swing with the eyes about the mentioned horizontal axis, and gravity control means for the eyes.

2. In an eye set, a pair of eyes, a supporting member extending between said eyes, connector members one for connecting each of the eyes with the supporting member, said connector members comprising parts providing for manual adjustment of the connector members rotatably and longitudinally of the supporting member, said connector members also having pivot parts by which the respective eyes are pivotally connected thereto to swing about vertical axes, a carrier for the supporting member permitting pivotal movement of the eyes with the supporting member upon a horizontal axis, eyelids, one positioned over the upper portion of each eye, each eyelid having an extension projecting therefrom to the rear of the respective eye and being attached to the adjacent connector member so as to be carried thereby to swing with the eyes about the mentioned horizontal axis and so as to be adjustable with the connector member rotatably of the supporting member, and gravity control means for the eyes.

3. An eye set comprising a pair of eyes, a cross rod extending between said eyes, connector members by which the eyes are pivotally connected with the cross rod, eyelids one arranged over the upper portion of each eye, the connector members having tangs projecting therefrom, and the eyelids having portions formed with openings through which said tangs engage for fastening the eyelids with the connector members, together with gravity control means for the eyes.

4. An eye set comprising a pair of eyes, a cross rod extending between said eyes, connector members by which the eyes are pivotally connected with the cross rod, eyelids one arranged over the upper portion of each eye, the connector members having tangs projecting therefrom, the eyelids having portions formed with openings through which said tangs engage for fastening the eyelids with

the connector members, and bumper means also held by said tangs, together with gravity control means for the eyes.

5. An eye set comprising a pair of eyes, a cross rod extending between said eyes, a supporting carrier for the cross rod arranged intermediate the eyes and providing a pivotal mounting for the cross rod upon a horizontal axis, connector members manually rotatably adjustably attached to the cross rod and serving to connect the eyes with the cross rod for pivotal movement therewith upon said horizontal axis, said connector members having pivot portions engaging the eyes whereby the eyes are pivotally attached to said connector members for movement upon vertical axes, gravity control means for the eyes, the eyes and the cross rod having parts co-operative to limit pivotal movement of the eyes in at least one direction upon said vertical axes, and a bumper member fixed to one of said connector members adjustable therewith with respect to the cross rod and adapted for limiting pivotal movement of the eyes in at least one direction upon said horizontal axis.

6. An eye set comprising a pair of eyes, a support by which the eyes are mounted to swing upon a horizontal axis, connecting members carried by the support and pivotally engaging the eyes providing pivotal mounting for the eyes upon vertical axes, the connecting members and the support including parts co-operative to provide independent pivotal adjustment of the connecting members and eyes with respect to the support upon the mentioned horizontal axis, eye lids fixedly attached directly to said connecting members to swing with the eyes about said mentioned horizontal axis and adjustable therewith with respect to the support, and bumper means also fixedly connected directly with the connecting members to swing therewith and with the eyes about said horizontal axis having parts to limit swinging of the eyes in at least one direction about said horizontal axis.

7. An eye set comprising a pair of eyes, a cross rod extending between said eyes, a supporting carrier for the cross rod providing a pivotal mounting for the cross rod upon a horizontal axis, separately formed eye lid members arranged one over the upper portion of each eye, a separately formed bumper member, connector members one for each eye, said connector members each having one part engaging the cross rod to provide rotary movement of the connector member with the cross rod upon said mentioned horizontal axis and being of a character providing pivotal adjustment of the connector member about the cross rod upon the mentioned horizontal axis, each connector member having other parts by which the respective eye is pivotally connected thereto to swing about a vertical

axis, each connector member having another part by which the respective eye lid is connected directly thereto to move therewith and with the eye about said mentioned horizontal axis and adjustably about the cross rod, one of said connector members having also a part by which the mentioned bumper member is connected directly therewith in a position to limit swinging movement of the connector member in one direction about the mentioned horizontal axis, and a gravity control for said eyes.

8. An eye set comprising a pair of eyes, a cross rod extending between said eyes, a supporting carrier for the cross rod arranged intermediate the eyes and providing a pivotal mounting for the cross rod upon a horizontal axis, a pair of connector members attached to the cross rod serving to connect the eyes respectively with the cross rod for pivotal movement therewith upon said horizontal axis, said connector members being each independently manually rotatably adjustable with respect to the cross rod, said connector members each having pivot portions engaging the respective eyes whereby the eyes are pivotally attached to the connector members for movement upon vertical axes, gravity control means for the eyes, and a pair of separate bumper members fixed one to each connector member to move at all times with its connector member and each having a part to engage a portion of a doll head to limit movement of its respective eye in at least one direction about said horizontal axis.

In testimony whereof we affix our signatures.

SAMUEL MARCUS.
ALEXANDER KONOFF.
